METAL POLE STRUCTURE

Walter F. Schulz, Youngstown, Ohio, assignor to
 Truscon Steel Company, Youngstown, Ohio, a
 corporation of Michigan

Application December 31, 1930
 Serial No. 505,889

9 Claims. (Cl. 189—25)

Skeleton poles and towers have been found entirely practical for carrying overhead wires and the like. Power lines and other wires affording means of communication between distant points often are located through remote and very inaccessible places. These towers or poles though relatively light in weight when assembled occupy considerable space and their cost of transportation becomes a matter of material consequence.

One of the primary objects of the present invention is to provide a structure that can be fabricated in complete units and shipped in "knockdown" condition, being so constructed that it can be readily assembled in the field. The structure moreover is such that the parts can be packed in close assembly and as a consequence a much greater amount of material can be loaded and transported within a restricted compass than is possible where the towers are built before shipping. The result is not only a great saving in transportation charges, but it makes it possible to more conveniently and practicably deliver the articles to isolated and inaccessible places where assembly and erection can be made.

In the accompanying drawings:

Figure 1 is a side elevation of a tower structure for power lines embodying the present invention.

Figure 2 is a top plan view of the same.

Figure 3 is a detail cross sectional view on an enlarged scale and on the line 3—3 of Figure 1.

Figure 4 is a detail vertical sectional view on the line 4—4 of Figure 3.

Figure 5 is a detail side elevation of one of the pole members on an enlarged scale and at the encircling reinforcement.

Figure 6 is a detail sectional view on an enlarged scale and on the line 6—6 of Figure 1.

Figure 7 is a detail sectional view on the line 7—7 of Figure 4.

Figure 8 is a detail sectional view similar to Figure 7, but showing a slightly modified form of construction.

While it will be understood that the structure may take various forms and be either a single pole or tower, a complete assembly for relatively heavy power lines is illustrated in Figures 1 and 2. As there shown, two poles 9 are employed that support a cross arm designated by the reference numeral 10. As the pole structures are similar, a description of one will obviously suffice for both.

The pole consists in the present instance of four separate units, though a less or greater number may be employed, depending on the cross sec-

tional form desired. Each of these units is designated by the reference numeral 11. Each unit consists of longitudinal side bars 12 preferably made of deformed plate metal, consisting of angularly disposed side flanges or walls 13 that are set at an obtuse angle. One of the flanges of each side bar is provided with a longitudinal inset bead 14. A web connects the side bars 12 of each unit and is preferably formed of a rod 15 bent to zigzag form, the bends 16 of this rod or web lying against the ribs 14 of the two side bars and being electrically welded thereto. The consequence is that a unit is provided which is very strong, but is substantially flat, the free flanges only being offset and these in divergent relation.

In assembled relation and in the embodiment disclosed, four units are employed, as will be clear particularly by reference to Figure 3, these units having the free flanges 13 of their side bars 12 arranged in overlapping relation. They are secured together as shown in Figures 4 and 7 at intervals by bolts 17 or other suitable fasteners. At certain points these fasteners may take the form of crossed brace rods 18 (see Figure 3), the terminals of which pass through the overlapped flanges 13 and are secured by suitable nuts 19.

These poles may furthermore be braced as shown in detail in Figures 5 and 6. That is to say corner plates 20 in the form of angle brackets are placed around the outer sides of the overlapped and secured flanges and are connected by angle bars 21. Connecting adjacent angle bars and extending on the inner sides of certain of the associated side bars 12 are crossed braces 22 and these crossed braces in turn are connected by diagonal angle bars 23 forming ties. This produces not only a hoop-like binder around the pole, but an internal brace for said pole.

It will be evident that with this structure the units may be fabricated at a manufacturing plant and practically nested in piles or bundles, inasmuch as one will lie within the other so that four of these units, for example, when lying flat, will not occupy nearly the amount of space that an assembled pole will occupy. The units however being complete in themselves, can be readily assembled by unskilled labor inasmuch as they need only to be placed in properly associated relation and the bolts or fasteners applied.

When a set of these poles or towers is employed for carrying a cross arm, the structure is preferably that of Figures 1 and 2. The poles or towers 9 are suitably assembled and their lower ends embedded in the earth, as shown. The

- cross arm 10 consists of a pair of skeleton beams. Each beam comprises a lower chord 24 and an upper chord 25. The chords are connected by a web formed of a zigzag rod 26 having its bends 5 welded or otherwise secured to the chords 24 and 25. As shown particularly in Figure 2, the two beams have a double bowed formation. In other words they have outwardly bowed portions 27. These portions at their widest point embrace the 10 upper ends of the poles or towers 9 and are fastened as shown at 28 in Figure 1 to the side bars of the units. Braces 29 may be interposed between the oppositely bowed portions of the two beams and where the beams most nearly approach each other, hanger brackets 30 are interposed between and secured to them. These hanger brackets, as will be readily understood, support the cables that are to be carried by the 15 structure.
- 20 From the foregoing, it is thought that the construction, operation and many advantages of the herein described invention will be apparent to those skilled in the art, without further description, and it will be understood that various 25 changes in the size, shape, proportion and minor details of construction may be resorted to without departing from the spirit or sacrificing any of the advantages of the invention.
- For example, the particular angular relation 30 of the flanges 13 of the side bars may be varied. Thus in Figure 8 angle bars 12a are shown having their flanges 13a of each disposed at right angles to each other. Each free flange however, overlaps a flange of the associated unit and the 35 parts are secured together by bolts as 17a. It will be understood that the webs here designated 15a are the same as those already described and are connected to the side bars 12a in the same manner.
- 40 What I claim, is:
1. A skeleton tower or pole structure for commercial purposes comprising separate units, each consisting of longitudinal side bars of angle metal, and a web of substantially zigzag form alternately secured to a certain flange only of each 45 of the side bars, the other free flanges extending to the inner side of the unit, said units when assembled having the other and inset free flanges of certain of their side bars overlapping the side bars of the other units and secured thereto.
  2. A skeleton tower or pole structure for commercial purposes comprising separate units, each consisting of longitudinal side bars of angle metal, and a web of substantially zigzag form having 55 its bends alternately welded to a certain flange only of each of the side bars, the other free flanges extending to the inner side of the unit, said units when assembled having the other and free flanges of certain of their side bars extending toward the other units and overlapping the side bars of said other units and secured thereto.
  3. A skeleton tower or pole structure for commercial purposes comprising separate units, each consisting of longitudinal bars of angle metal, certain of the flanges thereof being longitudinally ribbed, a web comprising a rod of zigzag formation having its bends welded to the ribs 70

of said flanges and lying alongside said flanges, said units when assembled having associated side bars with inset free flanges, the inset free flange of one bar longitudinally lapping the other bar, and fasteners securing said bars together. 80

4. A skeleton tower or pole structure comprising separate units, each consisting of longitudinal bars of angle metal having outer and inner flanges disposed at an obtuse angle in cross section, a web comprising a rod of zigzag formation having its bends welded respectively to the outer only of the ribs of said flanges leaving the other inset flanges free, said units when assembled having associated side bars, the free inset flange of one bar overlying the other bar, and 90 fasteners securing said bars together. 95

5. A skeleton tower or pole structure for commercial purposes comprising separate units, each consisting of longitudinal bars of angle metal having outer and inner flanges disposed at an obtuse angle in cross section, the outer of the same having a longitudinal rib, a web comprising a zigzag rod having its bends laid against and welded to the ribs of said flanges of the side bars, leaving the other inset side flanges free, said 100 units when assembled having certain of the side bars associated with their free flanges overlapped, and fasteners securing said overlapped flanges together. 105

6. A tubular tower or pole structure comprising separate units, each consisting of longitudinal side bars and an open web connecting the same, the adjacent side bars of associated units being overlapped, and cross braces within the structure connected to the overlapped portions 110 of the side bars. 115

7. A tubular tower or pole structure comprising separate units, each consisting of longitudinal side bars and an open web connecting the same, the adjacent side bars of associated units being secured together, a hoop surrounding the structure outside the associated units, braces connecting different portions of the hoop and extending across the space within the structure and ties connecting the opposite braces and extending 120 across the space within the tower or pole structure. 125

8. A structural unit for towers or poles for commercial purposes comprising spaced side bars of deformed plate metal having inner and outer angularly disposed flanges, and a web of substantially zigzag form bridging the space between the side bars and having its opposite sets of bends respectively lying alongside and welded to the sides of the outer flanges only, the inner flanges 130 being free of the said webs and extending toward and adapted to overlie and be secured to the corresponding free flanges of other units. 135

9. A tubular tower or pole structure comprising separate units, each consisting of spaced side bars and a skeleton web connecting the same, portions of the side bars being overlapped, and cross tie rods extending diagonally across the space within the tower or pole structure and having their terminal portions passing through 140 and securing together the overlapped portions of the opposite units. 145
